UNITED STATES PATENT OFFICE.

JOHN A. KATZ, OF YORK, PENNSYLVANIA, ASSIGNOR TO S. FORRY LAUCKS, OF YORK, PENNSYLVANIA.

KEY-IDENTIFICATION DEVICE.

Application filed September 22, 1926. Serial No. 136,994.

The invention relates to means for identifying keys by means of removable disks, and has for its object the provision of an improved means to hold the disk in position 5 in a recess in the key, and also means for permitting the removal of the disk from the recess if it is desired to change the identification disk in the key.

The invention relates particularly to keys 10 used for cylinder locks, and has particular reference to the customers' keys used in safe-deposit boxes, thus enabling the bank to change the identification indicia on a customer's box if he has lost his key to prevent unauthorized opening of the box by the finder 15 of the key. The invention also lends itself to marking the key with the name and address of the owner of the key so that the key may be returned when lost, and also to identify articles of furniture or other objects 20 to which the key may be applied.

The invention will be described in detail hereinafter and will be found illustrated in the accompanying drawings in which:

25 Figure 1 is a plan view of a conventional key showing the improved identifying device applied thereto,

Figure 2 is an enlarged detail showing the head of the key in section,

30 Figure 3 is a transverse sectional view on a plane indicated by the line 3-3 of Figure 2,

Figure 4 is a detail plan view of the identification disk,

35 Figure 5 a detail of the resilient ring for holding the disk in position in the recess of the key, and

Figure 6 is a sectional view on an enlarged scale on a plane indicated by the line 6-6 of 40 Figure 1.

In the drawings similar reference characters will be used to designate corresponding parts throughout the several views.

The key selected for illustration of the 45 improved identifying device is of the flat type, and designated 10, and has a head 11 that may be of the trefoil contour as disclosed, or of any other contour that may be selected. An opening 12 is provided in the

50 head 11 for the reception of the key ring, this structure being common in keys of this type. The head 11 is also provided with a recess 13, the walls of the opening 12 and recess 13 intersecting as shown to form an opening 14 for the purpose to be hereinafter

described. The wall of recess 13 is also provided with a circumferential groove 15. 16 indicates the identification device which is as shown in the drawings a disk, circular in shape, but it will be apparent that the shape 60 of the recess 13 and the disk 16 may be other than circular if desired by the manufacturer. Disk 16 is designed to carry identification indicia such as illustrated in the drawings or any other means for identifying the key 65 with the owner or for the purpose for which it is intended. This disk 16 is provided with a reduced circumferential flange 17, and 18 is a lug or projection or tab extending outwardly from the edge of the flange 17 and designed to fit in the opening 14 and extend into the opening 12 as clearly shown in the drawings, thus properly positioning the identification disk 16 in the recess 13, and at 70 the same time providing means for removing 75 the disk from the recess after the holding means to be hereinafter described has been removed. The holding means comprises a resilient split ring 19 that engages the flange 17 and seats in the groove 15 in the wall of 80 the recess 13.

After the device is assembled as shown in the drawings it will be apparent that the disk 16 may be removed from the recess 13 by removing the split ring 19 from engagement with the groove 15 by means of any sharp implement such as a pin, the pin to be engaged with the ring 19 at the opening 14 or when the grooves of the key extend so that they intersect the wall of the recess 13, 85 it will be apparent that removal of the ring may be effected by engaging the ring at the point where the grooves in the key intersect the recess. When the ring 19 has been removed then the disk may be raised from its seat by engaging the lug 18 with a pointed implement, or the disk will drop from the recess if the key is inverted, the principal function of the lug 18 in its relationship 90 with the opening 14 being to properly position the disk in the recess 13 when the disk is of the shape shown in the drawings, that 95 is circular.

What is claimed is:

1. A key identifying device, comprising a key having a head with an opening therethrough and a recess, the wall of said recess intersecting the wall of the opening and provided with a continuous groove, a disk carrying identification indicia adapted to seat 105 110

in said recess, a flange extending around the disk, a lug extending outwardly of said flange to extend into said opening, and resilient means adapted to engage the flange 5 and in said groove to hold the disk from displacement from the recess.

2. A key identifying device, comprising a key having a head with an opening therethrough and a circular recess, the wall of 10 said recess intersecting the wall of the opening and provided with a circumferential

groove, a circular disk carrying identification indicia adapted to seat in said recess, a flange extending around the disk, a lug extending outwardly of said flange to extend into said opening, and a split ring of resilient material adapted to engage the flange and in said groove to hold the disk from displacement from the recess. 15

In testimony whereof I affix my signature.

JOHN A. KATZ.
